UNITED STATES PATENT OFFICE

WILLIAM LEE PILKINGTON, OF ST. HELEN'S, ENGLAND, ASSIGNEE
PILKINGTON BROTHERS, OF SAME PLACE.

DESIGN FOR A PATTERN FOR PLATE-GLASS.

SPECIFICATION forming part of Design No. 22,753, dated August 29, 1893.

Application filed November 11, 1892. Serial No. 451,689. Term of patent 14 years. Patented in England April 21, 1892, No. 191,254.

To all whom it may concern:

Be it known that I, WILLIAM LEE PILKINGTON, a subject of the Queen of Great Britain, residing at St. Helen's, county of Lancaster, 5 England, have invented and produced a new and original Design for a Pattern for Plate-Glass, (patented in Great Britain April 21, 1892, No. 191,254,) of which the following is a specification, reference being had to the accompanying drawings, forming part thereof.

Figure 1 is a plan of a plate of glass showing my design. Fig. 2 is a cross-section of the same on line x, x , of Fig. 1.

The leading feature of my design consists 15 in groups of similar pyramidal raised rhomboidal figures, which figures, in each group, are arranged radially from a common center with their similar sides, respectively, in juxtaposition, and which said groups are 20 arranged in series with the groups of each series alternate to the groups of the adjoining series; together with other pyramidal raised rhomboidal figures arranged between, and with outlines corresponding to the outlines of, the outer ends of the aforesaid radially arranged figures forming the groups thereof.

At A, A' , are shown groups of similar pyramidal raised rhomboidal figures a , which 30 figures, a , in each group, are arranged radially from a common center, with their similar sides in juxtaposition or next to each other throughout the group. The said groups, thus constituted, are arranged in series with 35 the groups A of one series located therein alternately to the groups A' of the adjoining

series. At b are shown other pyramidal raised rhomboidal figures which are between the outer ends of radially arranged rhomboidal groups A, A' , thereof, which approach each other in the outlines of thereof, and with the sides of corresponding in outline or outline or contour of the adjacent outer ends of said figures.

The described design is on the surface of a plate of glass.

What I claim is—

The design for the pattern for plate-glass herein shown and described, the surprising groups of similar pyramidal raised rhomboidal figures, which figures, in each group, are arranged radially from a common center with their similar sides, respectively, in juxtaposition, and which said groups are arranged in series with the groups of each series alternate to the groups of the adjoining series; together with other pyramidal raised rhomboidal figures arranged between, and with outlines corresponding to the outlines of, the outer ends of those of the radially arranged rhomboidal figures which ends approach each other in the respective series of groups thereof, as set forth.

WM. LEE PILKINGTON
